UNITED STATES PATENT OFFICE.

WILLIAM S. HAMM, OF HUBBARD WOODS, ILLINOIS, ASSIGNOR TO THE ADAMS & WESTLAKE COMPANY, OF CHICAGO, ILLINOIS, A CORPORATION OF ILLINOIS.

SIGNAL-LAMP.

1,209,287.

Specification of Letters Patent. Patented Dec. 19, 1916.

Application filed January 19, 1914. Serial No. 813,029.

To all whom it may concern:

Be it known that I, WILLIAM S. HAMM, a citizen of the United States, and resident of Hubbard Woods, county of Cook, and State of Illinois, have invented certain new and useful Improvements in Signal-Lamps, of which the following is a specification, and which are illustrated in the accompanying drawings, forming a part thereof.

10 The invention relates to signal lamps especially adapted for railway service, and which are provided with a plurality of light emitting apertures to which are fitted lenses of different colors; the object of the invention being to provide improved means for screening some of the apertures in order to change the signal intended to be given.

More specifically it relates to a lamp of the top draft type provided with a conical chimney flue; and it consists in providing such a lamp with a conical opaque screen adapted to fit or nest within the chimney when not in service, and to be lowered to inclose the burner so as to cut off the light 25 from some of the lenses.

The invention is illustrated in the accompanying drawings, in which—

Figure 1 is a vertical section on the line 1—1 of Fig. 2; Fig. 2 is a plan section on the 30 line 2—2 of Fig. 1; Fig. 3 is a detail of the screen-actuating mechanism; and Fig. 4 is a detail side elevation of the screen.

The body or casing of the lamp is represented at 10, and its burner at 11. The casing is provided with a plurality of light-emitting apertures each provided with a lens, as 12, 13, 14, 15. In practice it is customary to use lenses differing in color, as red, white and green, and the signal intended to be given is indicated by the number and color of the lenses. The lamp is of the top draft type, having air induction ports 16 in its dome, a perforated screen 17 for delivering the air into the body of the 45 casing, and a conical chimney flue 18 above the burner.

A conical screen 19, of substantially the same shape and size as the chimney flue and adapted, when not in service, to nest therein, 50 is provided for cutting off the light from some of the light-emitting apertures, being movable downward to inclose the burner. The screen 19 is provided with an opening 20, adapted to register with one of the light-emitting apertures of the casing when in its

lowered position, thereby permitting the signal to be given by the use of a single lens.

The screen is carried and moved by means of a yoke 21, pivotally attached to it adjacent its lower end and having a rigid arm 22, which is attached to a lever 23, pivoted to the wall of the casing 10 and controlled from without the casing by means of a lever 24 pivotally mounted in an alcove 25 of the lamp casing, and having a pin 26 which engages a slot in the outer end of the lever 23.

When the outer end of the lever 24 is depressed to the position shown in Fig. 1, the screen is lowered to inclose the burner 11. When the outer end of the lever 24 is thrown up to the position shown in Fig. 3, the screen is raised to the dotted lines position of Fig. 1. A guide rod 27 depends within the chimney 18 and the screen 19, and, with the yoke, maintains the screen in upright position 75 when lowered and guides it to its seat within the chimney when raised.

The invention is of special value when applied to top draft lamps, as shown, in that it provides means for screening the light 80 without interfering with the circulation.

It is obvious that the screen may be without lateral aperture if it be desired to cut off the light from all of the lenses.

I claim as my invention—

1. In a signal lamp, in combination, a casing having a plurality of light-emitting apertures, a burner within the casing, a conical chimney flue above the burner, a conical opaque screen having a lateral light-emitting aperture, such screen being adapted to fit within the chimney and being movable to inclose the burner and bring its aperture into register with a light-emitting aperture of the casing. 90

2. In a signal lamp, in combination, a casing having a plurality of light-emitting apertures, a burner within the casing, a conical chimney flue above the burner, a conical opaque screen having a lateral light-emitting aperture, such screen being adapted to fit within the chimney and being movable to inclose the burner and bring its aperture into register with a light-emitting aperture of the casing, and means without 105 the casing for moving the screen.

3. In a signal lamp, in combination, a casing having a plurality of light-emitting apertures, a burner within the casing, a conical chimney flue above the burner, a 110

- conical opaque screen having a lateral light-emitting aperture, such screen being adapted to fit within the chimney and being movable to inclose the burner and bring its aperture into register with a light-emitting aperture of the casing, a yoke pivotally attached to the screen, a lever pivoted to the casing and to the yoke, and means without the casing for actuating the lever.
- 10 4. In a signal lamp, in combination, a casing having a plurality of light-emitting apertures, a burner within the casing, a conical chimney flue above the burner, a conical opaque screen having a lateral light-emitting aperture, such screen being adapted to fit within the chimney and being movable to inclose the burner and bring its aperture into register with a light-emitting aperture of the casing, a yoke pivotally attached to the screen, a lever pivoted to the casing and to the yoke, means without the casing for actuating the lever, and a guide rod depending within the screen.
- 15 5. In a lamp, in combination, a casing hav-

ing a plurality of light-emitting apertures 25 and means for introducing a supply of air in its upper portion, a burner within the casing, a chimney flue, a screen adapted to inclose the burner provided with an aperture adapted to register with one of the casing 30 apertures, its upper end being of less diameter than the lower end of the flue, and means for vertically moving the screen.

6. In a lamp, in combination, a casing having a plurality of light emitting apertures; 35 a chimney flue and a source of light within the casing, a screen for inclosing the source of light and being of less diameter than the flue and having a lateral aperture adapted to register with one of the apertures of the 40 casing when the screen is in its lower position, the axis of the screen and flue being alined, and means for raising the screen above the source of light.
